MEMORANDUM PAD HOLDER

Freeman O. Ehrler, Glendale, Calif., assignor of one-fourth to Wayne C. Schrage, Glendale, and nine one-hundredths to Louis A. Rickert, North Hollywood, Calif.

Application August 30, 1948, Serial No. 46,852

4 Claims. (Cl. 281—15)

1

This invention relates to holders for memorandum pads and pencils and particularly to a form thereof which is susceptible of use in a variety of manners.

An object of the invention is to provide a holder for a memorandum pad which may be used on a desk or table, or mounted on a wall or other vertical surface or which may be attached over the edge of a supporting means such as the common sun-visor of a motor vehicle.

Another object of the invention is to provide a memo pad holder which is so constructed and arranged that the usual cardboard back of the memo pad is utilized as the means for holding the pad within the case.

Still another object of the invention is to provide a memo pad holding case formed from plastic and having spring means incorporated therein adapted to serve as gripping members for securing the case over the edge of a sun visor or the like.

A still further object of the invention is to provide a memo pad holding case in which the gripping means for securing the case to a sun-visor or the like are so constructed and arranged as to remain within the confines of the case when not in use with resultant capacity of the case to be mounted on a wall or to be laid on a desk or table.

Still another object of the invention is to provide a memo pad holding case formed from molded plastic and having incorporated therein a resilient pencil holding means also formed of plastic.

With the foregoing objects in view, together with such other objects and advantages as may subsequently appear, the invention resides in the parts, and in the construction, combination, and arrangement of parts or their equivalents hereinafter described; reference being had to the accompanying drawings of a representative mode of execution of the invention, and in which drawings:

Figs. 1, 2 and 3 are front, side and rear views, respectively, of a representative mode of execution of the invention.

Figs. 4 and 5 are bottom and top end views, respectively, of the device in the position shown in Figs. 1, 2 and 3.

Figs. 6 and 7 are longitudinal, sectional views taken on the lines 6—6 and 7—7, respectively, of Fig. 3.

Fig. 8 is an enlarged transverse, sectional view taken on the line 8—8 of Fig. 1.

Figs. 9 and 10 are enlarged, transverse, sec-

2

tional views taken on the lines 9—9 and 10—10 of Fig. 3.

Fig. 11 is an enlarged, perspective view of the pencil holding element.

Fig. 12 is an enlarged, perspective view of one of the spring clip elements, and

Fig. 13 is an enlarged perspective view of the means for hanging the case on a wall or the like.

10 In the illustrated form of the invention, the case comprises a plastic molding 1 of generally rectangular outline, the upper end 2 being approximately the thickness of a memo pad and the case tapering to a thin edge 3 at the lower end. The outer side walls 4 and 5 are also curved toward the flat rear side 6. The case is provided with a rectangular recess 7 bounded by an upper end wall 8, side walls 9 and 10, and a lower end wall 11. A bottom cross member 12 extends across the recess 7 between the lower edges of the side walls 9, and 10; the lower face of said cross member being disposed slightly within the rear edges of the side walls to provide a clearance recess 13 for the cardboard backing of a memo pad. The top and bottom edges are spaced from the end walls 8 and 11 and the outer edge of the end wall 8 is provided with a ledge 14 adapted to overly the upper end of a memo pad placed in the recess 7 while the end wall 11 at its inner end is provided with a ledge portion 15 adapted to underly the backing B of a pad P which is first inserted in the transverse slot 16 between the cross member 12 and the end wall 8 and then inserted through the transverse slot 17 between the adjacent edges of the cross member 12 and the ledge 15 as best shown in Fig. 6.

The outer face of the case 1 above the recess 7 is provided with a shallow transverse recess 18, in which a pencil may be held, as indicated in

40 dotted lines, by the resilient curved tongue 19 of a clip element 20, the rectangular base portion 21 of which is located in a recess 22 formed in the outer face of the case and the base portion 21 is further provided with rearwardly extending

45 locating studs 23, 23 adapted to be received in corresponding holes formed in the outer wall of the case at the back of the recess 22. The recess 22 is of such depth that when the base 21 is placed therein and cemented in place, the outer face thereof will be flush with the outer face of the case, thus contributing to the neat appearance of the assembly.

Formed on the face of the wall 8 opposite the recess 7 at the ends thereof are rectangular recesses 24, 24 in each of which is cemented the

shanks 25, 25 of a pair of resilient clip elements 26, 26. The clips are preferably formed from a resilient plastic material and are formed with upwardly extending loop portions 27, 27 and each terminates in a forwardly extending lip 28, and a notch 29 by which the end of the clip can be grasped to pull it way from the rear face of the case so that it can be slipped over the edge of a vehicle visor V or the like and be clamped thereto by the resilience of the clips as indicated in dotted lines in Fig. 6. When not so mounted, the clips remain within the hollow interior of the base.

Midway between and extending parallel to the recesses 24, 24, is a third rectangular recess 30 in which is cemented the shank 31 of a hanger 32 having a portion 33 bent upwardly from the shank and which provided with a circular opening 34 having a somewhat smaller portion 35 at the upper side thereof. The rear face of the upturned portion 33 of the hanger is substantially flush with the rear face of the case and the opening 34 permits the hanger to be slipped over the head of a nail or screw S protruding from a wall W or the like (see Fig. 7) and then upon moving the case downwardly, the portion 35 of the opening will embrace the shank of the nail or screw back of the head and will prevent accidental dislodgement of the case 1. Preferably, the lower end of the case is provided with a shallow recess 36 the bottom of which is flush with the outer face of the ledge 15 to facilitate dislodging the final sheets of a memo pad mounted in the recess 7.

It will be noted that the case is so designed that it can be formed as a single plastic molding and that all of the walls are of substantially uniform thickness. The clips and hangers are all of simple design and lend themselves equally well to economical production. The assembly is equally simple; it being merely necessary to apply cement and insert the parts in place without the need for assembly fixtures to hold them in place. As a matter of fact, the assembly can be made and the assembled cases placed immediately in packing boxes with the cement drying after packing.

In the foregoing description, the use of terms such as "above," "below," "front," "rear" and the like have been employed with respect to a case mounted on a wall or on a visor. It will be understood that these terms have been employed to facilitate description only and that no limitation is to be implied from their use.

While I have described and illustrated one form of my invention, I do not intend, thereby, to limit myself to the exact form disclosed, and the invention embraces all such modifications in the parts and in the construction, combination and arrangement thereof as shall come within the purview of the appended claims.

I claim:

1. A holder for memorandum pads comprising a hollow body member of rectangular outline having front and rear face portions and having internally disposed side and end walls carried by said front face portion and extending toward said rear face portion; said walls being spaced inwardly from the periphery of the body member and defining a pad receiving recess therein, a back member connected only to said side walls and extending across said recess and disposed inwardly of and parallel to said rear face portion, a ledge protruding from one of said end walls into said recess at a point substantially in the

plane of said back member with the free end of said ledge combining with the adjacent edge of said back member to define a narrow transverse slot, and a second ledge protruding into said recess from the other of said end walls at a point adjacent the front face of said body member.

5 2. A holder for memorandum pads comprising a body member of rectangular outline having an upper end of greater depth than the lower end 10 and having a pad receiving recess spaced inwardly from the periphery of the body member and including a back member constructed and arranged to hold a pad having a relatively stiff backing element therein by interlocking engagement with the backing element of said pad; said upper end being hollow and adapted to serve as a housing for a resilient and extendible mounting means for said holder.

15 3. A holder for memorandum pads comprising a hollow body member of rectangular outline having front and rear face portions and having internally disposed side and end walls extending from said front face portion toward said rear face portion; said walls defining a pad receiving 20 recess disposed parallel to and terminating inwardly of said rear face portion, a back member carried by said side walls extending across said recess having its side edges spaced from said end walls, with resultant formation of a pair of 25 transverse slots across said recess, a ledge protruding from one of said end walls into said recess at a point substantially in the plane of said back member, a second ledge protruding into 30 said recess from the other of said end walls at a point adjacent the front face of said body member; said ledges, back member, and slots combining to form a holding means with which the backing element of a memorandum pad may be interlocked.

35 4. A holder for a memorandum pad having a relatively stiff backing element, said holder comprising a body member of rectangular outline and having a flat rear face and a front face generally tapering toward said rear face from the upper to the lower end of said body member, a pad receiving recess formed in said front face including means spaced inwardly of said rear face with which the backing element of a pad may be interlocked, a hollow space open to the rear face of the body member at the upper end of the body member above the pad receiving recess adapted to house a mounting means for said holder.
